UNITED STATES PATENT OFFICE.

HARRY ETHERIDGE, OF ZELIENOPLE BOROUGH, PENNSYLVANIA.

RAILWAY-TRACK CONSTRUCTION.

Application filed November 11, 1926. Serial No. 147,634.

Particularly, my present invention relates to railway track construction which includes the use of individual rail supports which do not span the space between the parallel rails of the track nor support both of the two parallel rails thereof, as do the cross-ties now in common use.

It is recognized in the railway track art that many important advantages attend the substitution of individual rail supports for cross-ties, such, for instance, as the provision of more extended support for the rail to relieve it from bending stresses, but the tendency of the rail to tip and roll both inwardly, toward the axis of the track, and outwardly of the rail, which is characteristic also of rails supported by cross-ties, appears in the use of individual rail supports. This tipping and rolling is due to the lateral shifting on the rails of the moving wheels.

Were a simple beam or block placed under the rail and longitudinally thereof to obtain an extended bearing of the rail on the beam or block, the beam or block would not "nest" in the ballast nor would the latter have any appreciable binding or anchoring effect on the rail support, but the latter would quickly work loose in the ballast, under the influence of the moving wheels, and would thus afford an unsafe support for the rail.

While the tendency to tip and roll inwardly—that is toward the axis of the track—is more pronounced in the case of individual rail supports than the tendency to tip and roll in the opposite direction or outwardly, both tendencies exist and must be corrected to obtain a reliable support for the rail.

I have found, by long continued experiment and also from extensive experience in the use of individual rail supports in regular track service, that the tendency toward inward tipping and rolling may be corrected by extending the area of the bearing of the rail support on the ballast at the inside of the rail, but if such bearing surface be too great in proportion to the bearing area of the support at the outside of the rail the tendency toward outward tipping and rolling is magnified.

As a practical solution of the problem thus presented, I have invented an individual rail support wherein the areas bearing on

the ballast at the inside and at the outside of the rail are properly proportioned so as to stabilize the support and to practically eliminate tipping and rolling in either direction.

In my improved individual rail support the bearing area at the inside of the rail is substantially twice that at the outside of the rail; and careful tests under standard railway track conditions have proven this improvement to be a solution of the problem.

My improved rail supports are preferably formed of reinforced concrete or like material, and if the supports be made with the inside and outside bearing areas of approximately the same width as the length of the portion of the support disposed beneath and sustaining the rail, a mass of material is required which renders the support too expensive to manufacture commercially and of such mass and weight as to render its transportation and handling and its installation in and removal from the track impractical.

To avoid these cardinal objections I form my improved individual rail supports of substantially cruciform shape, the longer member of the cross which may be termed the "beam" extending longitudinally of and under the rail to provide the same with adequate under-support, while the two shorter members which may be termed "stabilizing legs" extend from the center of the beam and at right angles thereto, and in alignment with each other.

The stabilizing leg which extends toward the axis of the track, and which may be termed the "inner stabilizing leg" has substantially twice the bearing surface on the ballast as has the "outer stabilizing leg" which extends on the outer side of the rail, and in the preferred embodiment of my improved individual rail support the two stabilizing legs are of substantially the same width, the inner stabilizing leg being substantially twice the length of the outer stabilizing leg.

To improve the nesting of the supports in the ballast, the horizontal top edges of the support are beveled and the top surfaces of the two stabilizing legs are at a lower level than that of the rail beam.

When installed in a track, the individual supports of the opposite rails are unconnected, for any connection or attachment between the opposite supports, either rigid,

hinged or flexible, destroys the balance between the stabilizing legs of the supports and renders the use of my improved rail supports of little or no advantage over the use of the usual cross-ties.

I have also invented a new and improved type of embedded metal reinforcement for my rail support, the same being of the general character of an open-work cruciform box-like skeleton.

Other novel features of construction, and also of arrangement of parts, will appear from the following description.

In the accompanying drawings, wherein I have illustrated the best embodiment of the principles of my invention now known to me, Fig. 1 is in part a top plan view and in part a horizontal section of one of the individual rail supports; Fig. 2 is an elevation of the same looking from the inside of the rail; Fig. 3 is a similar view of the reinforcing skeleton; Fig. 4 is a vertical section taken along the line IV-IV in Fig. 1; Fig. 5 is an enlarged perspective of the metal skeleton, and Fig. 6 is a plan view showing the parallel rails of a track each rail being provided with an individual rail support and said supports being unconnected together.

Referring to the drawings 1 and 1^a (Fig. 6) represent the parallel rails of a railway track, each supported from beneath by the individual rail supports 2, said supports being unconnected with each other.

The supports are substantially cruciform, the longer leg 3 being the rail-supporting beam which extends longitudinally of the rail to provide an extended support for the same, while the two transverse legs 4 and 5 which extend inwardly toward the axis of the track and outwardly away from said axis respectively, as shown in Fig. 6, are respectively the inner stabilizing leg and the outer stabilizing leg. The inner stabilizing leg 4 has approximately twice the area bearing on the road bed as has the outer stabilizing leg 5, and this proportion is preferably provided by making the legs 4 and 5 of substantially the same width but the leg 4 of substantially twice the length of the leg 5.

The top surfaces of the legs 4 and 5 are preferably at a lower level than that of the longitudinal beam 3 and the top edges of the support are preferably beveled, as shown. Thus the support may be more easily nested in and more securely anchored to the ballast.

The rail does not rest directly on the beam 3 as the result would be the direct transference of the jars and thrusts of traffic from the rail to the body of the support.

To prevent this, I provide the upper surface of the beam 3 with a sunken seat 6 of slightly greater width than the base of the

rail and extending along said beam to near each end thereof. In said seat I mount a cushion means which directly supports the rail. Said cushion means preferably comprises an under mat 7 which lies in the bottom of the seat 6 and an upper mat 8 which rests on the mat 7 and protrudes upwardly out of the seat. The mats are both preferably made of resilient material, such as rubber, asphalt composition and the like, or a combination thereof, the under mat being the more elastic while the upper mat is less elastic. The combined thickness of the mats is sufficient to prevent the rail being depressed into direct contact with the beam. 3. 80

Any convenient means may be employed to fasten the rail to the support. I prefer to employ rail fastening means of the character described and shown in Letters Patent of the United States No. 1,586,617 issued to me June 1, 1926, and in the drawings I show the screw sockets 9 which are anchored and embedded in the material of the rail support at either side of the seat 6 and adjacent either end of said seat, the fastener bolts 90 being screwed down into said sockets as will more clearly appear from said Letters Patent.

The character of metal reinforcement which I employ is shown assembled but un- 95 embedded in the concrete in Figs. 3 and 5. The preferred form of the same is of the following character.

10 represents a pair of parallel top bars and 11 a similar pair of bottom bars, the members of each pair being maintained in fixed spaced relation by horizontal cross bars 12 bearing against the under sides of the bars 10 and welded or otherwise secured thereto. The upper bars 10 and the lower 100 bars 11 are held in fixed spaced relation by the interposed post bars 13 whose ends are welded or otherwise secured to the bars 10 and 11. At the outer side of the bars 10 are bars 14 parallel therewith but shorter 110 and 15 represents similar bars outside the bars 11. The adjacent upper and lower bars 14 and 15 are held in fixed spaced relation by the post bars 16 interposed between them and welded or otherwise secured thereto. 115

17 represents a pair of upper parallel bars which are disposed at right angles to the bars 10 and cross beneath the same as shown in Fig. 5. 18 represents a pair of lower parallel bars, also parallel with the bars 17 120 which cross over the bars 11. The bars 17 are held in fixed spaced relation with each other by the cross bars 19 which are welded or otherwise secured to the under sides of the bars 17 and the bars 18 are similarly held in fixed spaced relation by the cross bars 20 which rest on the bottom surface of the bars 18. The bars 19 are welded or otherwise secured to the bars 17 and the bars 20 are welded or otherwise secured to the bars 18. 125

The bars 17 and 18 are held in fixed spaced relation by the post bars 21 interposed between the same and welded or otherwise secured thereto.

5 At their intersections the bars 17 are welded or otherwise secured to the bars 10 and 14, and likewise the bars 18 are welded or otherwise secured to the bars 11 and 15.

10 The sockets 9 are welded or otherwise secured to the bars 10 and also preferably to the end posts 13.

15 The upper bars 10 are positioned so as to extend longitudinally of the beam 3 beneath the seat 6 from end to end thereof and are close to the bottom of said seat so as to assume directly the jolts and thrusts of traffic, a slight covering only of concrete, say not more than a quarter of an inch to protect the metal from oxidizing, being provided for 20 said bars.

25 The metal bars are welded or otherwise connected together to form the skeleton before it is embedded in the concrete in casting the latter and is of shape corresponding to that of the support but of less dimension so as to be embedded in the concrete mass.

30 The welding is illustrated at 22 in Figs. 3 and 5.

35 It is apparent that by means of my improved metal reinforcing skeleton a rail support of relatively small dimensions and comprising a minimum mass of concrete may be employed without sacrificing either strength or durability in the support or efficiency in its functioning.

40 By the use of my improved rail support the tendency to tip or rock either inwardly or outwardly is corrected and a firm and stable support for the rails is provided.

45 It will be noted that owing to the positionings of the bars 10 beneath and longitudinally of the seat 6 and close to the bottom thereof the metal reinforcement relieves the concrete of the severe strains and jars of passing traffic, thus preventing any possibility of crushing, rupturing or cracking of the concrete. It is further evident that the attachment of the fastener sockets 9 directly to the metal reinforcing skeleton aids materially in the protection of the concrete mass 50

from the effect of the traffic which otherwise would prove injurious thereto.

I have found these individual rail supports in actual railway use much superior to any other character of rail support which I 55 have employed or seen employed during many years experience in railway construction and maintenance.

What I desire to claim is:—

1. An individual support for railway rails 60 comprising a reinforced concrete block of substantially cruciform shape, said support having a bearing surface to rest upon the ballast at one side of the rail supporting portion of substantially twice the area of the 65 corresponding bearing surface on the other side of the rail supporting portion, said support having embedded therein metal bars assembled together to form a frame of a shape corresponding to that of the block but of less 70 dimensions.

2. An individual support for railway rails comprising a reinforced concrete block of substantially cruciform shape comprising an extended beam portion supporting the rail 75 from beneath and alined stabilizing legs extending transversely of the plane of the rail, the leg extending inwardly of the beam portion having substantially twice the bearing area on the ballast as has the outwardly extending leg, said support having embedded therein a skeleton box of cruciform shape formed of metal bars assembled in fixed relation to each other. 80

3. An individual support for railway rails 85 comprising a reinforced concrete block of substantially cruciform shape comprising an extended beam portion supporting the rail from beneath and alined stabilizing legs extending transversely of the plane of the rail, the leg extending inwardly of the beam portion having substantially twice the bearing area on the ballast as has the outwardly extending leg, said support having embedded therein a skeleton box composed of metal 90 bars welded together. 95

Signed at Zelienople, Pa., this 4th day of November, 1926.

HARRY ETHERIDGE.
